(57) **CLAIM**

The ornamental design for an ultraviolet sterilization line lamp, as shown and described.

DESCRIPTION

FIG. 1 is a front elevational view of a first embodiment of an ultraviolet sterilization line lamp, showing our design, the first embodiment having fixed grilles;

FIG. 2 is a rear elevational view thereof;

FIG. 3 is an enlarged right side elevational view thereof;

FIG. 4 is an enlarged left side elevational view thereof;

FIG. 5 is a bottom plan view thereof;

FIG. 6 is a top plan view thereof;

FIG. 7 is a top-front-right isometric view thereof;

FIG. 8 is a front elevational view of a second embodiment of an ultraviolet sterilization line lamp, the second embodiment having movable grilles, with the grilles in a closed position;

FIG. 9 is a rear elevational view thereof;

FIG. 10 is an enlarged right side elevational view thereof;

FIG. 11 is an enlarged left side elevational view thereof;

FIG. 12 is a bottom plan view thereof;

FIG. 13 is a top plan view thereof;

FIG. 14 is a top-front-right isometric view thereof; and,

FIG. 15 is a top-front-right isometric view thereof with the grilles in an open position, the top-rear-left isometric view thereof being identical thereto.

The break lines throughout the figures indicate that the appearance of any portion of the ultraviolet sterilization line lamp between the break lines forms no part of the claimed design.

The broken lines throughout the figures show portions of the ultraviolet sterilization line lamp that form no part of the claimed design.
